INKING SYSTEM FOR SURFACE-DECORATING MACHINES

Edward William Hamant, Dayton, Ohio, assignor
to Oxford Varnish Corporation, Detroit, Mich.,
a corporation of Michigan

Application September 3, 1937, Serial No. 162,264

6 Claims. (Cl. 101—154)

This invention relates to a surface decorating mechanism and especially to a ink or pigment system for such a decorating mechanism.

The subject matter of the present application 5 is disclosed but not claimed in Patent No. 2,096,731, issued October 26, 1937.

The general object of the present invention is to provide an improved ink or pigment system for a surface decorating mechanism, such as, for 10 instance, a graining machine.

Another object of the present invention is to provide an improved scraper or doctor blade mounting and operating mechanism, so arranged that the scrapers or doctor blades may be quickly 15 and easily moved from contact with their respective printing members without disturbing the relationship of the scrapers, one to the other, and may be simultaneously adjusted relative to the printing mechanism.

20 A further object of this invention is the provision of an improved pigment or ink recirculating system and an improved operating mechanism therefor.

Other objects of the invention will become 25 more apparent from the following description, reference being had to the accompanying drawings, in which there is shown a preferred form of mechanism for carrying out the invention. The essential features of the invention will be 30 summarized in the claims.

In the drawings, Fig. 1 is a substantially horizontal section through a decorating mechanism, illustrating the relationship between my improved scraper mechanism for a pattern cylinder 35 and an offset printing member; Fig. 2 is a vertical section through the scraping mechanism, as indicated by the lines 2—2 on Fig. 1; Fig. 3 is an elevation of the scraping mechanism, the various printing members being omitted from the view; Fig. 4 is a side elevation, the decorating mechanism illustrating the pigment circulating system; Fig. 5 is a sectional detail, illustrating the pigment pump.

The pigment system with which this invention 45 is particularly concerned, is illustrated in the drawings as applied to a decorating machine of the type illustrated and claimed in the co-pending application heretofore referred to. This decorating mechanism is especially adapted for 50 the application of a decorative coating to metallic frames, such as sheet-metal automotive vehicle window frames by an offset printing process. However, it will become obvious that the present invention may be used with other types of 55 decorating mechanisms, as well as to decorate vari-

ous types and shapes of articles of manufacture.

The decorative mechanism shown in the drawings comprises a pattern cylinder 10, having mounted thereon a pattern 11. The pattern is preferably a intaglio printing plate cylinder having a continuous design etched therein. A coating of ink or graining paste is applied to the pattern and is forced into the depressions therein and the excess ink or paste is removed by the scraping mechanism with which the present invention is concerned, leaving only such pigment on the pattern as remains in the depressions in the plate. Mounted adjacent the pattern roll 10 are a pair of spaced rollers 14 and 15, around 10 which extends a transfer member 16 in the form 15 of a continuous flexible loop or belt.

This transfer member may be made of the usual glue and glycerin compound and is integrally mounted on a flexible base 17, the arrangement being such that as the rollers 14 and 20 15 rotate in the direction of the arrows shown in Fig. 1, the ink in the depressions in the pattern will be transferred to the offset printing belt 16 and from there, to the work W.

The pattern roll 10 and the offset belt supporting rollers 14 and 15 are mounted on respective shafts 18, 19 and 20. The shaft 18 is journaled in frame members 21, while the offset belt supporting roll shafts are journaled in a sub-frame 22, which is carried by the frame 21, as 30 shown in the copending application heretofore referred to.

The pattern 11 may be inked by a mechanism such as that shown and described in Patent No. 1,997,612, issued to Oxford Varnish Corporation, April 16th, 1935, and reference to such patent 35 may be had for a detailed description of such mechanism. Suffice it here to say that such inking mechanism comprises a vertically extending tube 30, in which is mounted a conveyor screw 31. The lower end of the tube is arranged to project into a reservoir 38 and is provided with an opening to permit ink to be drawn upwardly by the screw from the reservoir. The tube 30 is positioned adjacent and parallel with the surface 40 of the pattern 11, as indicated in Fig. 1, thus the ink drawn upwardly from the reservoir is fed out of a port or opening 37, and falls downwardly along the pattern 11.

The pattern roll shaft 18 and the offset roll 50 shaft 19 are provided with gears 32 and 33, respectively. These gears are driven by a power shaft 34 through suitable gearing 35. Secured to the upper end of the ink feed screw 31 is a pinion 36, which meshes with the pattern roll 55

gear 32, thus driving the various mechanisms in synchronism with each other.

The ink or graining paste which is applied to the pattern 11 by the ink supply mechanism is spread and the excess ink or paste is removed from the pattern 11 by a scraper mechanism with which this invention is particularly concerned. As shown, the scraper mechanism comprises a pair of doctor blades 50 and 51, the former co-acting with the pattern 11 and the latter co-acting with the transfer web or belt 16. Each of these doctor blades is secured to a vertically extending mounting plate 52. These mounting plates are provided with inwardly extending ears 54 adjacent their top and bottom ends, which are rotatably and slidably mounted on a shaft 55, which is secured to a bracket 56 by a set screw 47. The bracket 56 is pivotally mounted, as at 47, to the frame 21, which supports the pattern roll, and is secured in an adjusted position thereon by a set screw 48, which passes through an elongated opening 49 in the base of the bracket 56 and is threadingly secured to the frame 21. Thus, by moving the bracket 56, the relative position between the pattern roll and the doctor blade 50, as well as the position between the offset web and the doctor blade 51, is readily adjusted.

Normally, the doctor blades 50 and 51 are maintained in contact with the pattern 11 and the transfer belt 16, respectively, by a spring 60, interposed, as shown in Figs. 1 and 3, between the two blade mountings 62. However, when the decorating mechanism is inactive, these blades 55 may be manually swung out of contact with their respective elements by the rocking of a lever 61. This lever is secured to a shaft 62, carried in an upstanding ear 63 of the bracket 56, and has secured to its inner end a cam in the form of a lever 65. This lever, at each of its outermost ends, is provided with a roller 66, which, when the lever 61 is swung, engages the respective doctor blade mounting 52, thus urging them apart against the action of the spring, and bringing the doctor blades into the position indicated in Fig. 1, wherein they are separated from the pattern 11 and the web 16, respectively. Upon the return of the lever 61, the doctor blades both return to their active positions.

50 The adjustment of the pressure of the doctor blades 50 on the pattern is accomplished by swinging the bracket 56 relative to the frame 21. This likewise simultaneously adjusts the pressure between the doctor blades 51 and the work 52. 55 A separate adjustment, however, is provided so that the blades may be adjusted relative to each other. As shown, each blade is clamped to its bracket 52 by a clamping bar 58. This bar is held in position by set screws 59, which pass through 60 the bar, and through slotted openings in the doctor blades and are threadingly secured to the respective brackets.

Thus it will be seen that both doctor blades may be adjusted relative to the pattern and to 65 the transfer belt, and they may be moved out of contact with such members without interfering with the adjustment. These doctor blades may also be moved bodily as a unit, together with their supporting bracket away from the pattern and transfer belt, thus preventing inadvertent contact when the machine is to be idle over extended periods of time. Likewise, the arrangement is such that the doctor blades, their mounting and certain operating mechanism may 70 be removed as a unit from the machine, thus

75 facilitating the replacement of such units as well as facilitating the cleansing of the machine and the doctor blade unit.

Excessive wear on either the offset web 16 or the pattern 11 and the doctor blades 50 and 51 is prevented by reciprocating the blades vertically along the axis of their shaft 55. As shown, the doctor blade mountings 52 slidably embraces the shaft 55 and are normally urged downwardly toward the bracket 56, by a coil spring 70, which is interposed between the uppermost blade mounting 52 and an enlarged head formation 71 of the shaft 55. Slidably mounted in the bracket 56 are a pair of pins 73, which are secured to a block 74 which is slidably mounted on the lower end of the shaft 55 and underlies the bracket 56. A roller 75 is carried by the block 74, and, when the scraper mechanism is in an active position, is engaged by a lever 80, pivoted as at 81, to an ear 82 formed on the frame 21 of the decorating unit. This lever 80 is rocked by a cam 83, carried by a gear 84, which is mounted on the frame 21 and which is driven by a pinion 85 secured to the pattern roll shaft 18. The cam 83 coacts with a roller 86 secured to the inner end of the lever 80, thus swinging the lever about its pivot and causing the reciprocation of the scraper blade.

Ink removed by the doctor blades falls by gravity onto an inclined surface 21a of the frame 21 and thence through a passageway 90, into a trough or pan 91, which, as shown in Fig. 4, is supported beneath and by the frame 21. From the pan 91 the ink is returned to the reservoir 38 by a pump 100.

The ink or pigment pump 100 is best illustrated in Figs. 4 and 5. As there shown, this pump comprises a pair of telescopically arranged tubes 104 and 105. The upper one of these tubes is secured to a block 106, removably carried by the frame 21 and telescopically receives one end 40 of a tube 107, which conducts the ink from the pump to the reservoir 38. The lower end of the tube 104 is peened inwardly, as indicated at 108, and is normally closed by a ball 109, which is slightly less in diameter than the internal diameter of the tube 104. A spring 110 normally maintains the ball 109 in its lowermost position.

The lower pump tube 105 embraces the tube 104 and its lower end is normally closed by a spring-pressed ball 111. When, however, the tube 105 is raised relative to the tube 104, ink trapped between the two balls 109 and 111 forces the ball 109 upward, compressing the spring 110 and permitting such ink to enter the tube 104. When the tube 105 is moved downward relative to the tube 104, the spring 110 causes the ball 109 to close the passageway between the tubes 104 and 105, and causes a partial vacuum to be created in the tube 105. When, however, the ball 111 engages the bottom wall of the pan 91, this partial vacuum causes the ink in such pan to flow into the tube 105. Thus it will be seen that constant reciprocation of the tube 105 relative to the tube 104 will cause the ink to be drawn upward from the pan 91 and returned to the reservoir 38.

The pump tube 105 is reciprocated by the cam 83 heretofore described. As illustrated in Fig. 5, the tube 105 is connected by a link 112 with one arm of a bell crank 113, the other arm of which is provided with a roller 114. This roller is maintained in contact with the cam 83 by a spring 115, which is interposed between the bell crank and the pump support 117, which is removably secured to the frame 21.

From the foregoing description it will be seen

that there is provided a compact inking system, including an improved doctor blade mechanism, which may be removed as a unit from the machine and an improved ink circulating unit including the ink reservoir, the ink pan, the recirculating part which likewise are removable as a unit from the machine, and they are each supported by the pump support. Likewise, the ink feed screw is readily removed by releasing its clamp 118 (Fig. 5). Therefore, the inking system is easily cleansed or removed and a new system substituted therefore, thereby facilitating the change of colors and permitting the previous inking system to be thoroughly cleansed while the machine is in operation using a replacement system.

I claim:

1. In a surface decorating machine, a pattern, means to supply color to the pattern, scraping means coating with said pattern to remove surplus color therefrom, an offset printing member arranged to remove the remaining color from the pattern roller and transfer it to the work by a rolling action, a scraper to remove any color remaining on said member after the pattern has been transferred from the work, a support for both scrapers, means to move each scraper relative to said support and out of contact with the pattern and member respectively, means to remove said support and scrapers as a unit away from their coating members.

2. A surface decorating machine, a pattern roll member, means to supply color to the pattern roll, a scraper coating with said roll to remove surplus color therefrom, an off-set printing member in the form of a continuous flexible band and arranged to remove a design in color from the pattern roll and transfer such design to a workpiece by a rolling action, a second scraper arranged to remove the color remaining on said member after the design has been transferred from the work, a common support for both scrapers, means to simultaneously move each scraper relative to said support and out of contact with the roll and member respectively, means to move each scraper relative to each other and relative to said support and means to move said support and scrapers as a unit away from their coating members.

3. In a surface decorating machine, a pattern roll, means to supply color to said roll, a pair of spaced rollers having their axes substantially parallel with the axis of said roll, an offset member comprising a continuous belt looped around said rollers, one of said rollers supporting the

belt adjacent the pattern roll and the other of said rollers supporting the belt for cooperation with a workpiece, a pair of doctor blades, one of said blades engaging the pattern roll to remove excess color therefrom, the other of said blades engaging the belt in a region supported by one of said rollers to remove any ink from the belt remaining thereon after the work is decorated, a common support for said blades, means to move said blades relative to each other and said support, means to reciprocate said blades in a direction parallel with the axis of said roll, and a pivotal and removable connection between said support and the decorating machine whereby said blades and support may be moved as a unit relative to said roll and said rollers.

4. In a surface decorating machine, a pattern roll, a reservoir adapted to contain a supply of fluid decorating material, means to remove fluid from the reservoir and apply it to the pattern, 20 a scraper means to remove excess material from the pattern, a receptacle to receive such removed material and means including a pump operated by the pattern roller to remove the material from the receptacle and return it to the 25 reservoir.

5. In a surface decorating machine, a pattern roller, a cam operated thereby, a reservoir adapted to contain a supply of fluid decorating material, a pump to remove fluid from the reservoir and apply it to the pattern, a scraper to remove excess material from the pattern, a receptacle in to which such removed material may flow by gravity and means including a second pump operated by said cam to remove the material from the receptacle and return it to the 35 reservoir.

6. In a surface decorating machine, a frame, a pattern roll supported thereby, an offset printing member supported thereby, means removably secured to said frame to supply ink to said roll, a pair of doctor blades to remove excess ink from the pattern roll and from the offset printing member respectively, and means securing said mounting and said blades to said frame whereby 40 they may be removed from the frame as a unit, a receptacle adapted to contain a supply of ink for said first-named means, a second receptacle to receive the ink removed by said blades, a pump adapted and arranged to remove ink from the second receptacle and return such ink to the first-named receptacle, both of said receptacles and said pump being secured to said frame for removal therefrom as a unit.

EDWARD WILLIAM HAMANT. 55
